W. MITCHELL.

GAS GENERATOR.

APPLICATION FILED JUNE 16, 1913.

1,141,072.

Patented May 25, 1915.

UNITED STATES PATENT OFFICE.

WILLIS MITCHELL, OF MALDEN, MASSACHUSETTS, ASSIGNOR TO WILLIS MITCHELL COMPANY, INC., OF NEW YORK, N. Y., A CORPORATION OF NEW YORK.

GAS-GENERATOR.

1,141,072.

Specification of Letters Patent.

Patented May 25, 1915.

Application filed June 16, 1913. Serial No. 772,912.

To all whom it may concern:

Be it known that I, WILLIS MITCHELL, a citizen of the United States, residing at Malden, in the county of Middlesex and State of Massachusetts, have invented certain new and useful Improvements in Gas-Generators, of which the following is a specification.

The chief objects of this invention are to provide for regular and efficient generation of gas and perfectly even discharge thereof; to insure its fixed dry clear character or quality, and to insure the complete reduction into gas of all the gas producing elements of the fuel without permitting any of the latter to become burned or baked before generation and consequently accumulated on the walls of the generator. To these ends I employ a steadily tapering generating retort which necessarily offers a continual increase of resistance to the gaseous flow and a relief or regulating chamber containing an air cushion and having tubular connection with the inlet end of said retort as herein-after more fully set forth and claimed.

In the accompanying drawings: Figure 1 represents a vertical longitudinal central section of a fuel gas generator embodying my invention, also the front wall of the exterior casing, the pilot burner and the nozzle supplying the same being shown in side elevation. Fig. 2 represents a detail side elevation of the tapering central tube and core of the said generator, these two parts being shown separated and arranged side by side, omitting the gasket. Fig. 3 represents a detail end elevation on a smaller scale of said generator and burner and the pilot generator and burner used for preheating the main generator. Fig. 4 represents a sectional view taken on the line 4-4 of Fig. 3.

In said drawings the body of the retort or generator A is composed of an elongated steel cylinder or shell 1, constituting the outer portion of the greater part of the body of the generator, and a tubular cylindrical front section 2, screwed thereon and forming the front part of said body, provided with a tubular arm 3 extending obliquely upward and forward and having near its upper end a transverse cylindrical needle-valve casing 4, said parts 2, 3 and 4 being preferably cast in one piece from some composition, such as brass for example, which is a better conductor of heat than the cylinder 1 aforesaid,

in order that its protruding part may be heated by conduction from the inner part of said section which is exposed to the action of the burners and that the cooling of the gas in said protruding part and nozzle may be prevented; and the said cylinder and section being detachably screwed together. The forward end of section 2 is screw-tapped to receive a removable screw plug 5, which closes it. This plug is recessed in its inner end at 6 to receive the contiguous end of a closed metallic tube 7, fitting tightly therein, so that it may be conveniently withdrawn with said plug. The said tube 7 tapers gradually from its front end, where it is thus attached, to its rear end, which is almost in the same transverse plane as the rear end of said cylinder 1, though it may be slightly farther forward as shown. This smaller end is closed by a small plug 8. In effect this tube is a rod acting as a central core to cause the oil to flow in a thin space; since its interior is a closed air space. A solid rod of like diameter would, however, be less satisfactory, as it would absorb more heat in its greater mass and therefore would require more time to make it hot enough throughout for properly heating the oil.

The steel cylinder 1 has a brass lining 9, which will prevent rust or pitholes forming in the steel if dampness should work in with the oil from which the gas is to be generated. Of course this lining 9 will be unnecessary if the outer tube or cylinder 1 be made of brass or any material not easily oxidizable. The advantage of steel in said cylinder 1 is that it will be stronger in proportion to its thickness and less liable to sag when softened by intense heat; and for like reasons the closed tube 7 is also preferably made of steel; but a brass tube may be made strong enough, by increasing its thickness or otherwise, to answer my purpose in either case. A cap 10 having its outer end of frusto-conical form screws on the rear end of outer tube or cylinder 1, providing a space 11 within it at the inlet end of the retort or gas generator. Said space occupies somewhat more than the rear half of the interior of said cap and is partly cylindrical, partly frusto-conical in form. This inlet end is supplied with kerosene or other fluid hydro-carbon under pressure through an inlet pipe 12 from an oil-tank or any other suitable source. My chief object in this part of my

invention is to convert kerosene or other heavy hydrocarbon into a fixed gas for fuel promptly, certainly and cheaply, with no waste of material but the utmost possible yield of fuel gas. Such a generator or gasifier has long been a desideratum, those in use having hitherto been generally adapted to convert only the lighter hydrocarbons into fixed gas, or to convert the heavier hydrocarbons into vapor: and when it has been possible to convert the heavier hydrocarbons directly into fixed gas the expense has been too great and the result too unreliable for the procedure to rank as a practical success. One of the chief difficulties encountered has been the accumulation of soot or similar deposits of carbon on the walls of the generator. My central tube or core 7 has at its inner end a wire brush 13 for the removal of any dirt or sediment that may work in with the oil, this brush normally being kept in space 11, but scraping the inner face of lining 9 while it is being drawn out as above described. If this lining were absent the said brush would clean in like manner the inner face of cylinder 1. An annular gasket 14 of suitable material on tube 7 and removable therewith fits in section 2, forming a gas tight seat for the inner end of plug 5 and preventing any leakage at this point, while the parts of the generator are in operative position. Of course after such withdrawal this inner tube is readily cleaned at will. This brush is removably set into plug 8, so that a larger one, or one that is less worn may be readily substituted at any time. But this brush 13 merely has to deal with dirt or sediment other than carbon, owing to the special construction of my fuel gas generator, which is especially designed to gasify all of the oil, not allowing any carbon to be deposited in the retort. One of the provisions for especially guarding against this evil is the tapering construction of the core or central tube already referred to, which necessarily provides a reversely tapering cross-sectional area from rear to front of the retort chamber 15, formed by the thin annular space or retort chamber 15 between the core or closed tube 7 and the lining 9. The last named two parts do not touch at any point, but are much farther apart at their rear ends than at their forward ends, the diminution of diameter of the core 7 being progressive and very gradual. Consequently the inflowing volume of oil or hydrocarbon is continually being forced toward the relief tank by the backward impulses caused by the gas expanding under the influence of heat, while the gas is forced onward into a tubular passage of continually narrowing capacity, with necessary reaction, eddying and oscillation of movement, which of itself will tend to very efficiently dislodge

any carbon deposits from the faces of the lining and inner tube, should such take place. To aid such action, these faces should be polished, so that particles of oil may find it very difficult to adhere.

A means for relieving the back pressure and regulating the oscillations of the oil in the interior of the retort is found in a relief tank or chamber 16, which is mounted on and supported by a vertical branch pipe 17, extending up from inlet pipe 12 and containing air, so as to form an elastic cushion or air-spring above any oil which may be forced up into the same. Any excessive resistance in the retort would cause the oil to back up into said chamber compressing said air in the relief tank 16 and the counteraction of the latter would reinforce the normal pressure on said oil from behind, supplying more oil when the resistance lessens. There is thus an automatic compensating action in this relief tank or chamber which combines to keep up a regular continuous vibration in the retort or gas generating chamber 15. Of course the oil would not be forced up into this tank or chamber if the volume of that material in pipe 12 beyond it could be more easily driven back to its source, but this is not the case, the hydrocarbon oil being under such pressure from behind that it cannot be packed back upon itself against its own current to more than a very slight degree. Thus without the relief tank the oil would not receive so much motion and would in part bake on the walls. Of course it would be possible to substitute other elastic material for air—for example some other gaseous fluid in this relief chamber.

The needle-valve-casing 4 is provided with a removable conoidal nozzle 18 governed by a needle valve 19 which has a bearing 20 and stuffing-box 21. Said nozzle discharges fixed hydrocarbon gas into the outer end of the burner 22, which extends flush with or slightly beyond the front of the main casing 70 of the machine. As the parts 3 and 4 and the outer portion of section 2 are outside of the said casing and not directly acted on by the heating devices hereinafter described, it becomes desirable to provide for ready conduction of heat to them from the directly heated parts of the retort, thereby insuring the thoroughly heated condition of the gas until it is delivered to the burner. This is the reason for the use of a relatively high conducting composition instead of steel in the casting comprising these parts. The upper end of the bore of arm 3 is closed by a removable screw-plug 23, which provides for easily blowing out and cleansing this bore. No part of the retort is permitted to become red hot, yet the heat, the resistance of the tapering retort and resultant oscillating action are sufficient to turn kero-

sene oil to a fixed gas discharged as such into the said burner 22. This burner is cylindrical and parallel to said fuel gas generator or retort, being arranged within the casing and at no great distance therefrom and discharging against the same through the lower rows of very numerous perforations 24, the upper rows being directed upon the water tube helices hereinafter described. This burner is the continuous heating device of the said retort, though the latter is preheated by a pilot burner 25 supplied by a pilot retort 26, which may get its hydrocarbon from the same source as the main generator.

10 The two last mentioned devices communicate by means of an arm 27 corresponding to arm 3 and a nozzle 28 arranged like that hereinbefore described. The burner 25 supplied by said nozzle is first lighted. In this operation the nozzle 28 is heated by a torch, the gas having been turned on by opening the needle valve of said nozzle, and the holes of the burner 25 are lighted by a match or other simple means of ignition.

15 These pilot devices are convenient means for preheating the main fuel gas generator, but I am not confined thereto, as any others suitable to the other devices shown might be substituted without affecting the action of my main fuel gas generator. The pilot generator and burner of course may continue in action during that of the main generator and in practice this is most often done, so that the main generator will remain per-

20 manently under the converging blasts of flame of both burners and one of these will be also preheating its own supply from the pilot generator. The outlet of the retort through the nozzle is of course a fine orifice 25 governed by the needle valve. The inlet to said retort is through a pipe of moderate size (preferably about one fourth of an inch in diameter) as shown in Fig. 1, its area in cross-section being preferably a little greater than the average area in cross-section of the retort itself, the latter being, as before stated, the tapering space between the core 7 and lining 9. The said inlet is calculated to permit the back pressure of the gas in said retort to reach the relief chamber 16 through pipe 17. As so small a volume of gas can escape through the needle valve and as the tapering construction of the retort offers a steadily increasing resistance to its passage through the same there is naturally much back pressure and tendency to eddy, causing vibration or oscillation in the current and this will be more or less irregular unless some device be applied to secure uniformity by proper conservation and regulation. This is the purpose and utility of the relief chamber 16. By such a regulation I prevent any flickering or uneven action of the flame of the burner and the consequent injurious variation of its effect on said

25 gas generator and in the generation of steam or any other purpose to which it may be applied. What actually occurs within the retort or gas generator constructed and having the relief chamber as above described, is as follows—as nearly as can be determined from observation, experiment and tests of measurement: The hydrocarbon oil is vaporized or gasified by the heat of the generator on or before reaching two thirds of the length of the tapering retort 30 and its expansion, coacting with the liquid pressure behind it and the gaseous resistance before it, produces a series of oscillations, which prevents the oil from baking or burning on the inner walls of the retort. Nevertheless, the current flows on with increasing resistance, owing to the steady diminution of the retort passage, and the oscillations become shorter and more rapid 35 as the gas advances though they are kept uniform as stated at any particular point of the length of the retort by the action of such relief chamber, until at the discharge end of the retort they are so exceedingly 40 rapid as to be indistinguishable, making a practically unchanging condition of the outward flow at the nozzle so that the flame of the burner will be steady and of unvarying heat. The gas generator and burner as a combined 45 device will speedily come to a balance of conditions after the ignition of the pilot and will be steadily and efficiently operative without perturbation, except the oscillations ending in a practically non-vibratory 50 condition, the oscillations having become so frequent that the effect at the nozzle is as though they did not exist. The determining elements in this operation are the regularly 55 tapering shape of the retort and the relief chamber, forming an air cushion. Either of these provisions used alone would improve the gas generator; but both of them used in combination, are necessary to produce a 60 perfectly satisfactory result in producing gas without carbon deposits. Besides the 65 final regularity of discharge, the frequency of the oscillations and their continual increase in rapidity, subject to heat determined in degree by such outflow, will insure 70 the thorough transformation of the oil to a 75 permanently fixed gas, and will also prevent all carbon deposits from localizing on the metal surfaces of the retort, converting 80 practically all such material into gaseous 85 form and carry such gas forward with the 90 oscillating but advancing current, until they are reduced to gas like the other volatile 95 material. No carbon in solid form is left 100 to be removed by the brush or otherwise. 105 Besides mechanical-liquid oscillations above 110 described, there must necessarily be oscillations of temperature to some extent as the 115 hydrocarbon moves nearer to the parts of 120 the generator or retort, where the accu- 125 130

mulated heat has the greatest effect or back toward and beyond the inlet, where it is least and where the entering oil is cooler than the vapor or gas produced therefrom: 5 although the conductivity of the steel tube 1 and the other metal parts and the still greater conductivity of the section 2, as well as the action of the atmospheric air on the latter will modify this action and tend to 10 keep all the particles of the contents of the retort more nearly at a single temperature. Also there must inevitably be generation within said retort chamber 15 of electrical conditions and stresses from friction, the 15 change from liquid to gaseous form, the breaking up of particles and the oscillating movement of the hydrocarbon, and these conditions and stresses must oscillate likewise. There may be other vibratory movements, as yet not determined.

Having thus described my invention, what I claim as new and desire to secure by Letters Patent is:

1. A gas generator provided with an elongated retort chamber of thin annular tapering form, in combination with means for discharging heat directly on the exterior of said generator.

2. In a gas generator, a tapering core and 80 a cylinder external thereto, providing between them a tapering annular retort chamber adapted to receive fluid fuel at one end and discharge the same as fixed gas at the other, in combination with a burner arranged to discharge against the said cylinder.

3. In a gas generator, a pair of elongated horizontal parts, forming between them a retort chamber of thin annular form in cross 40 section, which tapers from the receiving end to the discharging end, and a burner arranged to direct flame against the exterior of the outer one of said parts.

4. An elongated, tapering, horizontal gas 45 retort chamber, in combination with an inlet pipe supplying the same at the larger end, a branch pipe extending from said inlet pipe out of the line of flow of the fuel to said chamber and a regulating tank in which 50 said branch pipe ends and which forms an air cushion to aid the operation of said retort chamber.

5. A gas generator provided with a gas 55 retort chamber, an inlet pipe and a regulating tank forming an air cushion connected to said pipe, said tank being supported at a higher level than the said retort chamber and permanently in communication therewith.

6. In a gas generator, a tapering retort chamber, an inlet pipe supplying the same at the larger end of said chamber, a branch pipe extending vertically upward from said 65 inlet pipe and a relief chamber supported by said branch pipe and receiving the upper

end of the latter in its bottom, the upper part of said air chamber providing a cushion of inclosed air.

7. A tapering retort chamber, in combination with a nozzle connected to its smaller 70 end, an inlet pipe discharging into its larger end, a branch pipe from said inlet pipe, and a relief tank containing an air cushion and connected to said branch pipe, but out of the line of flow of the fuel.

8. In a gas generator, an internally lined elongated outer shell and a tapering elongated core within the same arranged to form between them a thin retort chamber annular in cross section and tapering in the direction 80 of flow, an inlet pipe supplying the larger end of said retort, a branch pipe extending therefrom, and a relief tank connected to said branch pipe, but out of the line of flow of the fuel to said retort.

9. A retort chamber tapering in the direction of the line of flow, in combination with an inlet pipe, a branch pipe, and compressible and expansible means connected with said branch pipe out of the main line of flow, 90 but arranged to receive and store back pressure of said retort chamber and return the same to equalize the discharge of said retort chamber.

10. In combination with a cylinder constituting a part of the outer body of a gas generator, a separable section attached thereto and forming the front part of said body, a casing, through which the said front protrudes, and a removable core arranged within the said cylinder, the said cylinder and core leaving an annular elongated tapering retort between them.

11. In combination with a shell constituting the main part of the outer body of a gas generator, a section attached thereto as the front part of said body, a casing, through which the said section protrudes and a core within said shell, the space between said core and shell constituting a tapering retort 105 chamber of thin annular form in cross-section.

12. A gas generator having a detachable forward section comprising an inclined tubular arm and an integral needle-valve casing and provided also with an elongated cylinder extending rearward from said section and a concentric core, this cylinder and core being shaped to present a tapering retort chamber between them, said retort chamber having an inlet at its larger end.

13. In combination with a tubular part constituting the greater portion of the body of a gas generator, a section screwed thereon in forward extension of said body, and provided with discharging devices and screw-tapped at its front end, a screw plug turned into the said screw-tapped end and provided with a recess at its inner end, and a core 120 which fits at its proximate end into said re-

- cess and which is arranged within said tubular part, being of less diameter than the interior diameter of the latter, to form a retort chamber between them.
- 5 14. In combination with a tubular part of a gas generator and a core of less diameter within said part, leaving a space as a retort chamber between them, a nozzle and connections for discharging the gas generated in said retort chamber and a cap covering the inlet end of said retort chamber provided with an opening for the inlet of fuel, said cap providing a space or chamber between said opening and the inlet end of 15 said retort.
15. In combination with a main generator and a pilot generator, a pilot burner supplied by said pilot generator and arranged below said generators to discharge flame 20 continuously and permanently on both of them, and a main burner supplied by the main generator and arranged parallel to and above the latter to discharge flame on the outer shell of the said main generator.
- 25 16. In combination with a cylindrical horizontal gas generator, a pilot burner and

main burner, all three of these devices being cylindrical and horizontal, the said generator being arranged above one of the said burners and below the other and receiving 30 the converging jets of flame on its outer shell.

17. In combination with two burners, a gas generator which supplies one of them and is arranged to receive the jets of flame 35 from both of them on its exterior, one of the said burners being above said generator and the other burner being below it.

18. In combination with two burners, two gas generators, one of said burners being 40 arranged to discharge flame on both generators, both burners being arranged to discharge on one of the generators from above and below and the generators respectively supplying the burners individually. 45

In testimony whereof, I have signed my name to this specification in the presence of two subscribing witnesses.
